DRINKING GLASS

Edward J. Foster, Cincinnati, Ohio, assignor to
Agnes C. Foster, Cincinnati, Ohio

Application April 17, 1952, Serial No. 19,371

Term of patent 14 years

(Cl. D36—8)

To all whom it may concern:

Be it known that I, Edward J. Foster, a citizen of the United States of America, residing at Delhi Hills, Cincinnati, Hamilton County, State of Ohio, have invented a new, original, and ornamental Design for a Drinking Glass, of which the following is a specification, reference being had to the accompanying drawing, forming a part thereof.

In the drawing:

Fig. 2 is a top plan view; and

Fig. 3 is a bottom plan view thereof.

The characteristic features of my design reside in the reentrant upper portion in its relation to and association with the other portions as shown.

I claim:

The ornamental design for a drinking glass, as shown and described.

EDWARD J. FOSTER.
